DISPENSING DEVICE

Arthur Hammerstein, Great Neck, N. Y.

Application August 29, 1940, Serial No. 354,660

2 Claims. (Cl. 221—62)

The invention relates to dispensing devices and more particularly to devices for dispensing comminuted materials such as sugar, salt, pepper, and the like, from containers, and has for its object to provide a novel device whereby the comminuted contents may be dispensed in an accurately controlled manner and with maximum efficiency. The invention contemplates the provision of a novel dispensing device which constitutes a closure for the container with which it is combined and whereby the contents of said container normally are hermetically sealed against the effects of atmospheric changes. A further object of the invention is to provide a novel dispensing device which in operation develops crushing or expelling forces on the comminuted material whereby dispensing of said material is facilitated and clogging of the dispensing opening tending to interfere with and destroy the hermetic sealing action of the device is avoided. Other objects will appear from the description hereinafter and the features of novelty will be pointed out in the claims.

In the accompanying drawing, which illustrates examples of the invention without defining its limits, Fig. 1 is a perspective view showing the novel dispensing device in operation; Fig. 2 is a sectional elevation of a container equipped with the novel dispensing device; Fig. 3 is an enlarged sectional view of the dispensing device on the line 3—3 of Fig. 2; Fig. 4 is a similar view on the line 4—4 of Fig. 3; Fig. 5 is an external elevation of the novel dispensing device; Fig. 6 is a detail view illustrating the dispensing device in operation, and Fig. 7 is a detail view, partly in section, showing another form of the novel dispensing device.

The novel dispensing device, in all of its forms is in the nature of a resilient hollow cap generally constructed in a manner to provide the desired resiliency as by being made of an inherently resilient material such as rubber, said cap being arranged for attachment to a suitable container for the comminuted material to be dispensed.

As shown in the drawing, the device comprises a hollow body 10 having its upper end closed and provided with an annular bevel 11 and a sloping section 12 extending upwardly and inwardly as illustrated in Figs. 3 and 5. The section 12 is provided at an intermediate point with a slit 13 which is normally closed with its opposed surfaces in engagement with each other and in the operation of the device is converted into a discharge opening as will appear more

fully hereinafter; in the preferred arrangement the slit 13 extends through the section 12 in a direction to locate the opposite surfaces of said slit 13 in bevelled relation to said section 12 and substantially parallel to the major axis of the body 10 as shown in Fig. 3. In the illustrated examples the section 12 is formed with a raised annular bead 14 which surrounds and encloses the slit 13 as illustrated in Figs. 2, 6 and 7, and serves to prevent the latter from being torn in the operation of the device; if this protection is not required the bead 14 may be omitted. At diametrically opposite points the body 10 is provided with flat pressure surfaces or sections 15 which converge upwardly toward each other as shown in Fig. 4, and are each preferably of upwardly flaring or diverging form as illustrated in Fig. 5. In the preferred construction when the device is made of rubber or other resilient material, the body 10 is transversely thicker or heavier in registry with the pressure surfaces or sections 15 than it is at points between the same as indicated at a and b in Figs. 4 and 3 respectively. With this arrangement the body 10 at the pressure surfaces or sections 15 is of maximum efficiency in operation as will appear more fully hereinafter, and at points between said surfaces or sections 15 is of relatively greater flexibility.

In practice the novel dispensing device is designed for combination with a container for the comminuted material, in a hammer to constitute a closure for the open end thereof and preferably so as to be readily removed from said container and replaced thereon at will. Any convenient means may be utilized for combining the device with the receptacle which itself may be of any conventional type, although in order to secure the most efficient results it is preferred to construct the dispensing device and container as shown in Figs. 2 and 7.

In each of the illustrated examples the device is provided with an annular flange 16 located at the open end of the body 10 and with a second annular flange 17 located on said body 10 in spaced parallel relation to the flange 16 as shown in the drawing; the second flange 17 is preferably curved in cross-section or otherwise shaped in a corresponding way.

In the arrangement of Fig. 2 the dispensing device is combined with a container 18 which has its lower end closed by means of a removable cap 19 in screw-threaded connection with said container 18 as shown. At its upper end the latter is provided with an inwardly directed annular flange

20 which defines an opening having a diameter corresponding substantially to the external diameter of the portion c of the body 10 lying between the flanges 16 and 17. In order to provide a connection and a seal of maximum efficiency the width of the container flange 20 in the direction of the major axis of said container 18 is somewhat greater than the distance between the flanges 16 and 17 of the dispensing device or in other words is greater than the normal dimension of the portion c thereof in an axial direction.

To combine the dispensing device with the empty container 18, the cap 19 is removed and the dispensing device is inserted through the resulting open end and lengthwise of the container 18 and projected through the opening defined by the flange 20 at the opposite end of said container 18. At the point in this operation at which the flange 17 comes into contact with the inside surface of the flange 20, an outward push is exerted on the device sufficient to force the flange 17 out of the container 18 beyond said flange 20. This brings the flange 16 into engagement with the inside surface of the flange 20 and at the same time causes the flange 17 to engage the outside surface of said flange 20 as shown in Fig. 2. Because of the somewhat greater axial width of the flange 20, the portion c of the device is axially stretched by the aforesaid operation and is placed under a tension whereby the flanges 16 and 17 are firmly drawn against the opposite surfaces of the flange 20 to fix the dispensing device against relative rotation thereon. As a result of this developed tension in the body portion c the device is securely fixed in place on the container 18, and at the same time the co-operative action of the flanges 16, 17 and 20 provide an absolutely air-tight connection between the dispensing device and the container 18. As the slit 13 in its normal closed condition in which its opposed bevelled surfaces are in firm engagement with each other also is air-tight the dispensing end of the container is hermetically sealed when the device is in place on said container 18. The opposite end of the latter is correspondingly sealed by the cap 19 when the latter is in its operative position.

In the form shown in Fig. 7 the device is correspondingly combined with an internally threaded sleeve 21 arranged for threaded connection with the externally threaded neck 18^a with which the container 18^b is provided; in this form the bottom end of the latter may be permanently closed by means of an integral bottom in the conventional manner. The sleeve 21 is provided with an inwardly directed flange 20^a corresponding to the previously described flange 20 and likewise having an axial width somewhat in excess of the normal distance between the flanges 16 and 17 of the dispensing device. The latter is combined with the sleeve 21 by forcing the flange 17 through the opening thereof from the inside to bring the flanges 16 and 17 into engagement respectively with the inside and outside surfaces of the flange 20^a and to place the portion c under axial tension in the same way as set forth hereinbefore to thereby fix the device against relative rotation on said sleeve 21. To combine the dispensing device with the container 18^b in the form under discussion, the sleeve 21 is screwed upon the threaded neck 18^a to bring the flange 16 into firm engagement with the end face of said neck 18^a as illustrated in Fig. 7. When thus combined with the container neck 18^a the dispensing device also is securely fixed in place on the container 18^b and

at the same time hermetically seals the same as in the form first described.

The comminuted material may be introduced into the container 18 by removing the cap 19 and without disturbing the dispensing device, while in the form shown in Fig. 7 it is necessary to remove the dispensing device by unscrewing the sleeve 21 from the neck 18^a to enable the comminuted material to be introduced into the container 18^b.

In use the container 18 or 18^b is grasped in the hand and tilted downwardly toward its dispensing end with the thumb and forefinger in engagement with the opposite pressing surfaces or sections 15 as shown in Fig. 1. When the container 18 or 18^b occupies the inverted angular dispensing position shown in Fig. 1, the interior normally sloping surface of the sloping section 12 occupies a substantially horizontal position and constitutes a collecting surface for the comminuted contents of the container 18 or 18^b. In other words, in this dispensing position the comminuted material in the container 18 will pass into the interior of the body 10 and rest upon the interior surface of the normally sloping section 12 in easy accessibility to the slit 13 as will be apparent. When it is desired to expel the comminuted material, pressure is exerted by the thumb and forefinger upon the opposite surfaces or sections 15 to force the same toward each other. This pressing action of the thumb and forefinger of the device spreads the opposite bevelled surfaces of the slit 13 apart and converts said slit 13 into a discharge opening as illustrated in Fig. 6. This permits the comminuted material to escape through the open slit 13 as shown at d in Fig. 1, this dispensing of the comminuted material continuing as long as the pressure of the thumb and forefinger upon the surfaces or sections 15 continues. By manipulating the thumb and forefinger in a manner to alternately press upon the surfaces or sections 15 and to relieve said surfaces from such pressure, the comminuted material within the body 10 is subjected to an intermittent crushing or expelling force tending to expel said comminuted material outwardly through the open slit 13; in this way the amount of comminuted material which is dispensed may be accurately controlled as to its amount. When the pressure of the thumb and forefinger upon the surfaces or sections 15 is discontinued, the slit 13 automatically returns to its closed position. Because of the bevelled form of the opposed surfaces of said slit, any grains of comminuted material remaining in the slit 13 at the termination of the dispensing operation will automatically be forced from said slit 13 so that a complete closing of the latter is at all times automatically attained. As a result of this arrangement the container is always hermetically sealed when not in use to thereby protect the comminuted contents against any atmospheric changes which may take place so that said contents are always in condition for easy dispensing. The device is accordingly always of maximum efficiency in the dispensing of comminuted material such as sugar, salt, and the like, regardless of the atmospheric conditions which may exist at the time. The relatively greater thickness of the portion a of the device facilitates the camming action of said device in forcing the comminuted material outwardly through the open slit 13 while the relatively thinner portion b provides an inherent elasticity or resilience in said device which increases its operative efficiency. The annular bead 14, which may be omitted if not required, serves to prevent the material in the sloping sec-

tion 12 from being torn as a result of the forces developed when the normally closed slit 13 is converted into a discharge opening.

The device is simple in construction and may be readily combined with the container for which it is designed, it being understood that the form shown in Fig. 7 is utilized in the same way as described with respect to the other form shown in the drawing.

While the device is particularly effective for dispensing sugar, salt, pepper, and the like, it may be used with equal efficiency for dispensing other types of comminuted materials.

As previously stated herein it is preferred to construct the dispensing device of rubber or other inherently resilient material; it is to be understood however that this is not to be construed as precluding the use of other materials in its construction in combination with means for providing the desired resiliency.

Various changes in the specific forms shown and described may be made within the scope of the claims without departing from the spirit of the invention.

I claim:

1. In a dispenser for comminuted materials, the combination of a rigid container having an open end and adapted to contain a supply of the comminuted material to be dispensed therefrom, a dispensing device connected with said container and projecting beyond the open end of said container to normally constitute a seal and closure for the open end thereof, said dispensing device comprising a hollow resilient body in unobstructed interior communication with said container and freely accessible for compression beyond the open end thereof and having an interior flattened end surface, and a normally sloping section constituting part of said dispensing device and comprising an interior sloping surface leading to said flattened end surface and an approximately parallel outer sloping surface, said sloping section having a normally closed slit extending transversely therethrough from said outer sloping surface to said interior sloping surface in substantial parallelism with the major axis of said dispensing device, said interior sloping surface being substantially horizontal in an inverted angular dispensing position of said container to provide a collecting surface for the comminuted contents thereof, and said slit being convertible into a substantially vertical discharge opening in said angular dispensing position of said container, by inward compression of said

zontal in an inverted angular dispensing position of said container to provide a collecting surface for the comminuted contents thereof, and said slit being convertible into a substantially vertical discharge opening in said angular dispensing position of said container, by inward compression of said resilient body to force the comminuted material against said interior flattened end surface and outward through said discharge opening.

- 10 2. In a dispenser for comminuted materials, the combination of a rigid container having an open end and adapted to contain a supply of the comminuted material to be dispensed therefrom, a dispensing device connected with said container and projecting beyond the open end of said container to normally constitute a seal and closure for the open end thereof, said dispensing device comprising a hollow resilient body in unobstructed interior communication with said container and freely accessible for compression beyond the open end thereof and having an interior flattened end surface, a normally sloping section constituting part of said dispensing device and comprising an interior sloping surface leading to said flattened end surface and an approximately parallel outer sloping surface, said sloping section having a normally closed slit extending transversely therethrough from said outer sloping surface to said interior sloping surface in substantial parallelism with the major axis of said dispensing device, said interior sloping surface being substantially horizontal in an inverted angular dispensing position of said container to provide a collecting surface for the comminuted contents thereof, and said slit being convertible into a substantially vertical discharge opening in said angular dispensing position of said container, by inward compression of said
